UNITED STATES PATENT OFFICE.

EDWARD TINKHAM GIBSON, OF BROOKLYN, NEW YORK.

GAME-BOARD.

1,352,510.

Specification of Letters Patent. Patented Sept. 14, 1920.

Application filed February 26, 1920. Serial No. 361,517.

To all whom it may concern:

Be it known that I, EDWARD TINKHAM GIBSON, a citizen of the United States, and a resident of New York, borough of Brooklyn, in the county of Kings and State of New York, have invented a new and Improved Game-Board, of which the following is a full, clear, and exact description.

My invention relates to game-boards for games that are played on a flat game-board provided with markings denoting "stations" that are to be reached by a player in the progress of the game.

The object of my invention is to provide a game-board having a station-bearing section and a dial-bearing section; the latter having a move-directing dial face printed on it, and the said dial-face having in connection with it a pointer-piece adapted to be whirled on a pivot-member positioned at the center of the dial-face so that when the pointer-piece comes to rest it may indicate on the dial-face the particular "move" on the station-bearing section of the game-board that the player is to make with his "man."

This object is accomplished by the game-board illustrated in the accompanying drawings in which Figure 1 is a face view of a game-board disclosing an embodiment of my invention.

Fig. 2 is an end view of the same.

Fig. 3 is a cross-sectional view through Fig. 1 on line 1 and 1.

In this specification the parts are referred to by numerals, and these latter are connected to the parts to which they refer by lines.

2 indicates a flat base having a station-bearing section 3 and a dial-bearing section 4.

On the said station-bearing section 3 are printed a plurality of station-denoting markings, of which the reference numerals 5, 6, 7, and 8 refer to several. These said station-denoting markings are arranged in predetermined positions with relation to each other and each is provided with a station-number as are the station-denoting markings (or "stations" as they are called by users of this game-board) 5, 6, 7 and 8, which just mentioned "stations" are provided with station-numbers "6," "13," "12," and "11," respectively.

On the said dial-bearing section 4 of the base 2 is printed a dial-face 9 having a concentric ring section 10 which is subdivided by printed lines into a plurality of segmental sections, of which latter the refer-

ence numerals 11, 12, 13 and 14 indicate several. On each of the segmental sections in the said concentric ring section 10 is printed the station-numbers of at least two of the "stations" on the station-bearing section 3 of the game-board, as in Fig. 1 the station-numbers "34," "58" and "3" are printed on the segmental section 11. The said dial-face 9 also has a concentric ring section 15 which is subdivided by printed lines into a plurality of segmental sections, of which latter the reference numerals 16, 17, 18 and 19 indicate several. On each of the segmental sections in the said concentric ring section 15 is printed either the numeral "1," or "2," or a cipher.

The reference numeral 20 indicates a pivot member which is positioned at the center of the said dial-face 9. This pivot member consists of a vertically-positioned shaft 21, (see Fig. 3) on which is mounted a sleeve 22 having at its lower end a flange 23. The said shaft has a cap 24 at its upper end, and the body portion of the shaft is longitudinally divided into two coöperating sections 25 and 26 which extend through an opening 27 (see Fig. 3) in the base 2 of the game-board and are bent in opposite directions against the under surface of the said base 2 to draw the said cap 24 of the shaft into engagement with the upper end of the said sleeve 22 and to draw the said flange 23 of the sleeve into engagement with the upper surface of the said base 2.

Loosely mounted on the said sleeve 22 is a pointer-member 28 adapted to be caused to whirl on the said pivot member when given a swift stroke by the finger of a user of the game-board.

In the game that is played on this game-board, the first one and the last one of the numbers displayed on each of the segmental sections in the concentric ring section 10 (as, for instance, the numbers "34" and "3" in the segmental section indicated by the reference numeral 11) indicate, respectively, the "starting" station and the "terminal" station of a particular tour of travel that the competing players of the game (usually two) are to undertake with their "men" on the station-bearing section 3 of the game-board should the said pointer member 28, after being whirled, point to it when the pointer-member comes to a rest; and for the reason just given, this concentric ring section 10 is called by me the

"tour-indicating section" of the dial-face 9. Furthermore, in the game that is played on this game-board the numeral displayed in each of the segmental sections in the concentric ring section 15 (as, for instance, the numeral "1" in the segmental section indicated by the reference numeral 16) indicates the number of "moves" from "station" to "station" on the station-bearing section 3 of the game-board that a player can make with his "man" when the pointer member 28 comes to a rest after his giving it a whirl; and for the reason just given, this concentric ring section 15 is called by me 15 the "move-indicating section" of the dial-face 9. Opposite the innermost end of each of the lines dividing said section 15 into segmental sections is a numeral indicating the number of "moves" a player can make 20 should the said pointer member 28 come to a rest directly opposite one of these dividing lines.

In combination with the plurality of station-denoting markings or "stations" on 25 the station-bearing section 3 of the game-board is a system of lines, of which latter the reference numerals 29, 30, and 31 indicate several, whereby the said "stations" are connected one to another. I call these 30 just described lines "travel-lines" as a player's "man" must travel on one of these lines when moving from one "station" to another.

In the game that is played on this game-board a one-cent coin makes an excellent "man" for a player to use.

What I claim is:

1. A game-board comprising a base having a station-bearing section and a dial-bearing section, a dial-face printed on the upper surface of the last mentioned section, a pivot member projecting upwardly from the center of said dial-face, and a pointer member loosely mounted on said pivot member and adapted to be manually set whirling on a plane parallel with that of the upper surface of said dial-face; the said station-bearing section having on its upper surface a plurality of printed station-denoting markings having a distinctive station-number in connection with each, and a plurality of printed lines constituting a system of travel-lines connecting the said station-denoting markings one to another; the 55 said dial-face having a concentric ring sec-

tion subdivided by printed lines into a plurality of segmental sections each of the latter having on it printed numbers corresponding with at least two of the station-numbers on the said station-bearing section 60 of the base of the game-board, and said dial-face also having a concentric ring section subdivided by printed lines into a plurality of segmental sections each of the latter having on it a printed numeral; and the said 65 pivot member consisting of a sleeve mounted on a vertically positioned shaft having a cap at its upper end, the said sleeve having a flange at its lower end and the said shaft having its body portion longitudinally divided into two coöperating sections the free ends of which latter are bent in opposite directions against the under surface of the said base to draw the said 70 cap into engagement with the upper end 75 of said sleeve and said flange into engagement with the upper surface of the base of the game-board.

2. A game-board comprising a base having a station-bearing section and a dial-bearing section, a dial-face printed on the upper surface of the last mentioned section, a pivot member projecting upwardly from the center of said dial-face, and a pointer member loosely mounted on said pivot member 80 and adapted to be manually set whirling on a plane parallel with that of the upper surface of said dial-face; the said station bearing section having on its upper surface a plurality of printed station-denoting markings having a distinctive station-number in connection with each, and a plurality of printed lines constituting a system 85 of travel-lines connecting the said station-denoting markings one to another, the said 90 dial-face having a concentric ring section subdivided by printed lines into a plurality of segmental sections each of the latter having on it printed numbers corresponding with at least two of the station-numbers on 95 the said station-bearing section of the base of the game-board, and said dial-face also having a concentric ring section subdivided by printed lines into a plurality of segmental sections each of the latter having on it a printed numeral.

EDWARD TINKHAM GIBSON.
